PENCIL LEAD AND THE METHOD OF
MAKING THE SAME

Leonard E. Best, Summit, N. J.

Application December 28, 1939, Serial No. 311,323

2 Claims. (Cl. 120—83)

This invention relates to pencil leads, and to the method of making the same.

The invention relates to the manufacture of lead pencils, and has special reference to the preparation of leads and crayons intended to be used when sheathed in a wooden casing and held therein by glue, or other water soluble adhesive.

In the manufacture of black leads (so-called), it is customary to impregnate the clay graphite mixes with waxes after baking. In distinction to black leads which are made with graphite and clay, colored leads or crayons usually do not contain graphite or clay but do contain a considerable portion of wax. The waxy surface of these leads is water repellent, and in consequence the glue usually used in uniting the two sheaths of the wooden casing enclosing the leads, while it adheres to the wooden sheaths of the casing, does not join with the lead or crayon, whereby a looseness of the core of the pencil in respect to its sheathing casing results.

Many various attempts have been proposed to overcome difficulty, and to increase the structural strength of the pencil point by treating the lead in such a manner that an adhesion of the lead core with the sheaths of the wooden casing is brought about to such an extent as to bond the lead and sheaths together.

One of these methods is the sulphuric acid dip to destroy the waxy surface. Another is to use chemical crystals between the core and the grooves of the casing; another is to subject the core of lead before it has been placed into the casing to a mechanical action, one of such mechanical means being the sand blast process.

The objections to these various methods of the prior art are that they are essentially dirty, dangerous to the operatives and relatively expensive, and as regards those that utilize the mechanical processes of indentation by sand blasting, for instance, while the peripheral surface of the leads are subjected to indentations, the wax which permeates the entire clay graphite mixture is merely compressed at such peripheral surface, and therefore is still present when the glue is being applied. While some of these attempts overcome certain objections, they present others.

This invention overcomes many objections of the prior art, and it is simple, clean and inexpensive in operation; and the invention consists generally in the treatment of leads, either such as are known as black leads made of the clay graphite wax mixture, or the colored leads made of pigment and wax, to an electrical arcing ac-

tion along the entire peripheral surface of the leads.

As the black leads contain graphite which is a conductor, the lead is used as a part of the electric circuit and subjected to an arcing action, whereas since the colored leads made of pigment and wax are non-conductors, they are not used as conductors but are subjected to the action of an electrical arc which acts upon the peripheral surface of the lead to remove the outer peripheral surface insofar as the wax film is concerned, in the same manner as in the case of the arc upon the black lead used as a conductor. The wax film being secured, in consequence, the clay graphite constituents on the one hand, and the pigment constituent on the other, come into direct contact with the glue in the sheaths of the casing and thereby an intimate adhesion between lead and casing is obtained, as a result of which the lead core, be it black lead or colored lead, is securely held in the wooden casing and by such a secure holding the lead pencil at its point is structurally strengthened.

The invention will be further described in regards to the embodiments thereof, which will be shown in the drawing, and the invention will be finally pointed out in the claims.

In the accompanying drawing:

Figure 1 is a plan view of the improved machine which is utilized for the treatment of pencil leads made of clay, graphite and wax;

Figure 2 is a side view thereof;

Figure 3 is a drawing taken from a micro-photograph of the outer surface of the lead after it has been treated in the machine shown in Figures 1 and 2;

Figure 4 is a transverse section taken on line 4—4 of Figure 3;

Figure 5 is an enlarged transverse section of the lead while it is being moved in the machine shown in Figures 1 and 2;

Figure 6 is a transverse section of the lead as imbedded in the two sheaths forming the casing; and

Figure 7 is a drawing of two electrodes with the colored lead therebetween whereby the colored lead is subjected to the arcing action of the electrodes.

Similar characters of reference indicate the same parts throughout the various views.

Referring to the drawing, and more particularly to Figure 6, there is shown a finished lead pencil made up of the sheath 10 and the sheath 11, each having a semicircular bore 12 which is provided with glue. Within these two

semicircular bores 12 there is placed, after the glue has been applied thereto, a lead 13 which forms its core. The glue is also applied between the peripheral surfaces of the sheaths 10 and 11, 5 as at 14, and joins these together. This is known.

The invention is shown as embodied in an enlarged view of the core 13 as shown in Figure 4, and this shows that the outer peripheral surface is irregular and partly pitted and partly 10 otherwise removed by attrition, as shown by the various cavities relatively large or small indicated by 15 in Figure 4. These indentations result from the removal of the wax film or coating of the lead. The removal of the wax somewhat inside 15 of the initial periphery, is brought about by rotating a lead as shown in Figure 5, while moving the same, and subjecting it to an electric arc. In Figure 5 the general direction of the movement of the lead 13 is indicated by the arrow 16, 20 and which movement is brought about by a pushing action of an upright rod 17 secured to a belt 18 moving in the direction of the arrow 19. Above the belt there are guide rods or tracks 20 upon which the lead 13 rests. By the movement 25 of the lead 13 in the direction of the arrow 16, it is rotated in the direction of the arrow 21, and as the lead 13 is part of an electrical circuit passing through the guide rail or tracks 20, an 30 arcing action takes place as indicated by 22, as the circular outer surface of the lead circumferentially leaves the guide rail 20. This arcing action acts upon the wax, and the high temperature of the arc probably volatilizes or decomposes the wax, and in consequence removes 35 the same from the peripheral surface of the lead.

In Figure 5 the lead is shown in the position where about three-quarters of its circumference has already been acted upon and the remaining circumference, that indicated generally by 23, is 40 relatively smooth, i. e., it has that smoothness usually attendant leads after they have been prepared and are generally ready for insertion in the casing.

In Figure 3 is shown a reproduction of a micro- 45 photograph showing the actions of the arcing upon the lead, described in connection with Figure 5.

The important thing, therefore, is to subject 50 a lead consisting of a mix of clay, graphite and wax to an arcing action such as described in connection with Figure 5, as a result of which the exterior peripheral surface of the lead will have the wax portion removed so that the remainder of the composition such as the clay and graphite 55 may readily bind with the glue when the pencil is being completed in commercial form, as described in connection with Figure 6. There is, of course, wax within the lead, and it is desirable to encase the arc-treated lead before the inner 60 wax oozes to the free from wax surface.

One manner of treating the leads in accordance with the description of Figure 5 is shown in Figures 1 and 2. In the embodiment of the device or machine there shown, which may be varied 65 so as to carry out the actions described in connection with Figure 5, there are in Figure 2 three standards 30, 31 and 32, and adjacent the standard 30 is a supply hopper 33 supplying the leads 13 to the machine, and adjacent to the other end standard 32 is a collecting member 34 to receive 70 the leads which have been subjected to the electrical action. These standards 30, 31 and 32 each support in suitable bearings, shafts 35, which in turn support drums 36 or the like upon 75 which belts 37 and 38 are carried. One belt 37

is centrally disposed as shown in Figure 1, and two belts 38, each narrower than the belt 37, are disposed in spaced relationship to each other. The belts are actuated by a pulley wheel 39 and belt 40, and by the operation of the pulley wheel 39, the shafts 35 are rotated due to the action of the belts.

Referring now to Figure 1, it will be seen that disposed at either side of the belt 37 there are tracks 20, and in the embodiment shown these 10 tracks 20 converge from the standard 30 towards the standard 31. These tracks 20 are each connected with an electrical conductor, one conductor being indicated by 41, and the other by 42, and these conductors 41 and 42 are suitably connected with an electrical circuit operated by a switch 43, the electrical circuit having a transformer 44, the circuit being an alternating current circuit. Between the standards 31 and 32 the guide rails 20 also converge, and they converge 20 towards the standard 32, and these guide rails or tracks 20 are continuous from the conductors 41 and 42, so that they are also under the action of the electrical current, the ends of the tracks 20 being insulated from each other 25 by a suitable space or by a block of insulating material 45.

As each of these tracks 20 are substantially one from the standard 30 to the standard 32, the arrangement of the belts 37 and 38, as before described, is made, namely, in the wider space between the tracks 20, the belt 37 is between the tracks 20, whereas when these tracks converge to almost contact with each other, the belts 38 are spaced at each side thereof. Another 35 reason for this arrangement is that it is desirous of subjecting the entire peripheral surface of each lead, as it moves from one end to the other of the machine, to the arcing action described. The belts themselves are provided with upright standing rods 17, and these rods are arranged in pairs, each pair acting upon a lead.

The operation of the machine described is as follows. The leads, and in this case the black leads made of a clay graphite mixed with wax, 45 are inserted into the hopper 33, and they automatically drop upon the belt 37. As they drop upon this belt 37, a pair of upright rods 17 abut against each lead, and due to the movement of the belt in the direction of the arrow 47 the leads 50 are moved in the direction of the arrow 47 and roll upon the tracks 20 at each side of the belt 37. It will be noted that the lead now indicated by 13a has its two ends within the tracks 20, so that the electrical arcing action takes place upon 55 the lead from end to end inwardly. As the belt 37 moves the lead 13a to the position of the lead 13b, the arcing action works towards the center until the position of the lead reaches about that of 13c. Thereafter, the lead is moved by the 60 two belts 38, and the electrically actuated tracks 20 act upon the inner portion of the lead 13c as shown in Figure 1 until when the lead 13c reaches the position shown in Figure 1, the central portion of the lead has been arced, and thereby the 65 arcing action has taken place throughout the entire length of the lead, and, due to the rotation of the lead, has taken place throughout the circumference thereof.

In connection with the arcing action upon 70 crayons or colored leads, the lead 50 is subjected to a rotation action as shown by the arrow 51 in Figure 7 by roller means, and is moved longitudinally by suitable means through a gap 52 between the electrode 53 and the electrode 54. 75

By the action of the arc between the electrodes 53 and 54, the peripheral surface of the colored lead 50 is thereby acted upon in substantially the same manner as described in connection with the leads 13 in Figure 1.

It has been seen that in treating black leads, the conductivity of the graphite is utilized to carry an electric current through the lead, and by rolling the leads over a suitable set of tracks 10 which form a part of the same electrical circuit that thereby a continuous series of small electrical surface discharges that destroy the waxy surface are obtained, whereby the leads so treated 15 may be properly glued in the wooden sheaths which form the casing. It has also been seen that in treating crayons which are non-conductors, the crayon is subjected to a continuous electrical discharge or electrical arc that completely surrounds it and carbonizes the surface 20 waxes.

In both of these methods, relatively low voltages and current densities are used, so that they are essentially inexpensive and simple. The degree of treatment is readily controlled by the 25 usual electrical instruments giving a wide range of effects at the will of the operator. The action of the process of treating the leads is rapid, and the necessary equipment so compact and inexpensive that it can form a very flexible addition 30 to the existing processes for pencil manufacturing, and can be included in such a way that the processed leads can conveniently be used directly after processing before any deterioration takes place. It will be remembered that the wax 35 permeates the entire lead, and it is therefore preferable to encase these leads within a reasonable time after their electrical treatment, to prevent the wax from the interior of the leads from oozing out to the surface.

40 When pencils are made using leads processed in the manner described and bonded to the sheaths, they are structurally strong and give greater service than those made with the conventional untreated leads.

45 The manifold indentations of various con-

figurations relatively large and small and varied in regards to contour, serve as an excellent interstitial surface for the entrance of the glue, and bring about a binding effect between the lead core and the casing.

It is believed that the wax which is acted upon by the electric arc or arcing action in either volatilized or carbonized, the carbonization due to the high temperature of the arc being probably of the character of coking. It is now generally 10 said that carbonization takes place up to 350° F. or 400° F., and coking above 500° F., and high temperature coking between 1000° F. and 1200° F. Graphitizing of carbon takes place beyond 1200° F., and generally around 1800° F. to 2300° 15 F. or 2500° F. Wax used for impregnating leads melts at about 170° F. or 180° F. and volatilizes or decomposes at about 400° F., these temperatures depending upon the particular constituency of the wax.

20 Various changes may be made in the structural features of the machines described, the invention here being also the treatment by an electrical arc action upon the peripheral surface of a waxed lead, be it graphite or colored, whereby the peripheral surface is brought into a condition to obtain a permanent binding effect with the enclosing casing, and various changes may be made within the principle of the invention described without departing from the scope of the sub- 25 joined claims.

I claim:

1. The method of treating pencil leads which consists in subjecting the peripheral surface of the pencil leads to the action of an electrical 35 arc throughout the exterior peripheral surface of the lead, whereby the waxy peripheral surface is removed, whether film or otherwise.

2. An improved lead consisting of a pencil lead having a peripheral surface substantially free 40 from waxy constituents with indentations or interstices upon said surface of the character resulting from an electrical arcing action upon a pencil lead.
